(57) **CLAIM**

The ornamental design for a body buffer, as shown and described.

DESCRIPTION

FIG. 1 is a front perspective view of a first embodiment of a body buffer showing the design;

FIG. 2 is a front elevational of a first embodiment of a body buffer;

FIG. 3 is a rear elevational of a first embodiment of a body buffer;

FIG. 4 is a left side elevational of a first embodiment of a body buffer;

FIG. 5 is a right side elevational of a first embodiment of a body buffer;

FIG. 6 is a top plan view of a first embodiment of a body buffer;

FIG. 7 is a bottom plan view of a first embodiment of a body buffer;

FIG. 8 is a front perspective view of a second embodiment of a body buffer showing the design;

FIG. 9 is a front elevational of a second embodiment of a body buffer;

FIG. 10 is a rear elevational of a second embodiment of a body buffer;

FIG. 11 is a left side elevational of a second embodiment of a body buffer;

FIG. 12 is a right side elevational of a second embodiment of a body buffer;

FIG. 13 is a top plan view of a second embodiment of a body buffer; and,

FIG. 14 is a bottom plan view of a second embodiment of a body buffer.

The broken lines shown in the drawings are for illustrative purposes only and form no part of the claimed design.
